MAINE.

FILLING-END CONTROLLER.

1,275,684.

Specification of Letters Patent. Patented Aug. 13, 1918.

Application filed March 18, 1915. Serial No. 15,301.

To all whom it may concern:

Be it known that I, HENRY J. HEDLER, a citizen of the United States, residing at Taftville, county of New London, and State of Connecticut, have invented an Improvement in Filling-End Controllers, of which the following description, in connection with the accompanying drawings, is a specification, like letters on the drawings representing like parts.

The invention to be hereinafter described relates to looms, and more particularly to looms of the filling replenishing type, wherein the filling is replenished from time to time when that in the running shuttle has become either broken or substantially exhausted. Such replenishment may be effected either by discharging the shuttle and substituting a fresh one provided with a working supply of filling or by discharging the filling carrier or bobbin from the shuttle and placing a fresh carrier or bobbin therein having a supply of filling wound thereon. While certain features of the present invention are applicable to either type, the present exploitation of the invention will be made in connection with the type wherein the filling carriers or bobbins are changed, such, for instance, as in U. S. Patent, No. 529,940.

In this general character of loom, means have been provided to part or sever the old filling between the cloth selvage or edge and the shuttle at or about the time of filling replenishment, the object being to permit the filling carrier or bobbin as it was discharged, to draw the trailing end of the filling out of the shuttle-box and through the shuttle eye, and thus clear these parts so that the filling end would not be drawn into the shed. This only partially responded to the requirement, and at times the trailing end of the old filling would be caught by the shuttle or the new filling and on the pick or picks following replenishment, would be carried into the shed, and imperfect cloth would result.

Attempts have been made to overcome this deficiency by providing means to engage and hold the filling between the discharged carrier and the shuttle, the idea being that on the next pick, the shuttle would move away from the old filling and be unthreaded. This has not fully responded to the requirements, because the old filling being still in the shuttle box between the wall of the box and

the exterior of the shuttle, and threaded through the shuttle eye, it was liable to be broken between the shuttle and discharged carrier and the loose piece carried into the shed. Other attempts have provided means for supporting the filling near the limit of forward lay movement and between the shuttle and discharged carrier, the backward movement of the lay being relied upon to draw the filling out of the shuttle and shuttle box, as indicated for instance, in the Marcoux Patent, No. 766,151. The effectiveness of this manner of operation, however, depended upon the lay movement. With these generally-stated conditions in view, the present invention, broadly stated, aims to provide a filling or thread catcher which shall engage the old filling between the discharged filling carrier or bobbin and the shuttle-box and be moved in a direction to withdraw the filling from the shuttle-box and shuttle. An important feature of the invention, therefore, consists in giving the thread catcher a withdrawing movement in a plane transversely of the loom and in a downward direction relative to the shuttle-box to withdraw the thread from the shuttle-box and shuttle even when a filling end of considerable length extends from the abandoned filling carrier.

Another important feature of the invention consists in giving to the thread catcher a swinging movement in a plane extending transversely of the loom and in a direction toward and downward relative to the outer end of the shuttle-box. A further feature of importance consists in normally maintaining the thread catcher in initial or idle position until the indicating mechanism calls for a change of filling and to then render the thread catcher operative to perform its withdrawing function at or just subsequent to the time the shuttle is moved by the picking mechanism.

These features of the invention in the present instance, therefore, are carried into effect by an arm mounted for swinging or pivotal movement at a point below the path of the lay movement or in other words, below the shuttle-box at the replenishing side of the loom; and to insure engagement of the thread or filling by the catcher between the shuttle-box and the ejected carrier or bobbin, the upper or engaging end of the thread catcher is bent or formed with a

hooked portion, which, as the catcher performs its thread-withdrawing movement, engages the filling. In some cases, the filling-engaging or hooked upper end of the thread 5 catcher may be provided with teeth to effect a more sure or positive engagement with the filling and its withdrawal from the shuttlebox and shuttle, but such teeth are obviously not always essential. The thread catcher 10 may be actuated after a replenishing operation from any convenient source of power, and in the present instance, is illustrated as operated from the picking mechanism.

The above characteristics of the invention 15 and other features thereof will best be made clear from the following description and accompanying drawings of one form of means for carrying the invention into practical effect, it being understood that the particulars 20 of the means employed may be varied without departing from the true scope of the invention which is defined by the claims.

In the drawings:—

Figure 1 is a front elevation at one side 25 of a filling replenishing loom of the "Northrop type," showing the present invention associated therewith;

Fig. 2 is a sectional side elevation of sufficient parts of such loom showing the relation 30 of the present invention thereto;

Fig. 3 is a section on the line 3—3, Fig. 1; and

Fig. 4 is a detached detail of a good, practical form of thread catcher and its guide.

The loom frame 1, having mounted thereon the usual filling feeder or hopper 2 carrying the reserve filling carriers or bobbins 3, the ratchet 4 and the means for turning the feeder to bring a new filling carrier into 35 position for transfer after a filling replenishing operation, may be of the usual type. Likewise, the transerrer 5 having the downwardly-extending and connected arm 6 provided with the pivoted member or arm 7 to 40 be actuated by the bunter 8 mounted on the lay 9, may be as usual in this well-known form of filling-replenishing loom, and being well understood by those skilled in the art, specific and detailed description thereof is 45 unnecessary.

Looms of this general character have been provided with means to part or sever the old filling between the cloth selvage and shuttle upon call for filling replenishment, and such means is typified herein by the part 10, the end portion of which may constitute the thread-parting means and a shuttle feeler. The shuttle feeler and parter may be of any appropriate design, one form of which is 55 indicated in Patent No. 718,957, and the purpose of such thread parter, so far as the present invention is concerned, is to sever or part the thread between the cloth selvage and shuttle, when the filling is to be changed.

In looms of this type, the transfer shaft 11

has an arm 12 thereon, which, upon call for filling replenishment, places the shuttle feeler and thread parter in position to perform their respective functions, and as these features of structure and operation are well known to those skilled in the art, a more detailed illustration and description thereof is herein unnecessary, since the particulars constitute no essential part of the present invention.

The lay 9 carries the usual shuttle box 13 at the replenishing side of the loom, and a corresponding shuttle box at the opposite end of the lay, that at the replenishing side being provided with a bottom slot 14 through which the filling carrier 3 in the shuttle may be discharged when the new filling carrier is transferred from the feeder to the shuttle upon call for filling replenishment. Extending down from the slotted bottom portion of the shuttle box, as indicated in Fig. 2, there is usually placed a guide or chute 15 over which the discharged filling carrier, as indicated by dotted lines, Fig. 1, travels after being ejected from the shuttle. The parts so far described are, or may be, of usual character and construction.

When filling replenishment is effected in a loom of this general character, the filling which leads from the carrier or bobbin to be discharged, is parted between the cloth selvage and shuttle, and the carrier or bobbin from which it leads, is ejected from the shuttle and a new one substituted therefor. Since the old filling is parted as indicated, it follows that there is a trailing end of filling still in the shuttle box between the wall of the shuttle box and shuttle, and passing through the shuttle eye; and this may not be withdrawn as the old filling carrier or bobbin is discharged from the shuttle, so that on the next or following picks, this filling end is liable to be carried into the shed and cause imperfect cloth to be woven. The present invention, therefore, aims to effect a complete withdrawal of this filling end to thereby insure that on the subsequent pick or picks, production of perfect cloth will continue. In carrying out this aspect of the invention, a device is provided to engage the old filling between the shuttle-box and the discharged filling carrier or bobbin and move in a general downward direction relative to the shuttle-box, so that the filling end may be completely withdrawn from the shuttle and shuttle-box even though of considerable length. The device, which for identification will hereinafter be termed a thread catcher, is preferably given a swinging movement in the arc of a circle transversely of the loom about a center below the lay or shuttle-box so that the filling end is whipped or suddenly withdrawn from the shuttle and shuttle-box. For the best result, the thread catcher is moved from an initial

position in the described path transversely of the loom toward the outer end of the shuttle-box and has a bent or hooked upper portion to insure engagement with the filling.

Inasmuch as the thread catcher has no function to perform during the normal operation of the loom while sufficient filling is present in the shuttle, it is desirable that the thread catcher may remain quiescent during such normal operation, and be placed in operative condition upon call for filling replenishment. While the thread catcher may be moved at the desired time by any appropriate moving portion of the weaving instrumentalities, it has been found desirable to impart such movement at or about the time the shuttle is picked, and to this end the thread catcher, as will hereinafter appear, is so associated with the picking mechanism that upon call for filling replenishment, means for actuating the thread catcher are thrown into operative condition with respect to the pick mechanism, so that the said thread catcher acts to withdraw the filling end from the shuttle-box at or just after the time the shuttle is started by the picking mechanism. This arrangement enhances the whip-like action imparted to the filling end, and serves effectively to free the shuttle box and shuttle. Mounted upon the step 16 near the lower part of the loom frame, is the picker stick 17 which receives motion as usual, through the connection 18 with the arm 19 fixed to the pick rock shaft 20. The pick rock shaft 20 is carried in appropriate bearings, one of which is shown at 21, Fig. 2, and has extended therefrom, the usual roller 22 which is adapted to be engaged and moved by the picking cam 23 on the cam shaft 24. The picking mechanism just described may be of usual construction.

Extending from a bracket 25, Fig. 2, is an arm 26, on one end portion 27 of which is mounted the thread catcher.

In the present form of the invention, the thread catcher comprises an upwardly-extending arm 28 having a deflected upper portion, as shown, to insure engagement of the filling below the shuttle-box and between it and the ejected carrier or bobbin as the thread catcher is moved to perform its withdrawing function. It may be desirable in some cases to provide the thread catcher with the thread catching teeth 29 at its upper portion, which are adapted to engage the filling thread between the shuttle and the discharged filling carrier and hold it positively when the thread catcher is swung about the end portion 27 of the shaft 26. As a convenient means for mounting the arm 28 of the thread catcher upon the end portion 27, the latter has loosely mounted thereon, the sleeve 30 having a socketed por-

tion into which the end of the thread catcher arm 28 projects and is secured by a bolt 31. Surrounding the arm 26 is the spring 32, one end of which is secured to the arm by a pin 33, and the other end of which engages with the catcher arm 28, as at 34, the construction being such that the spring 32 normally acts upon the catcher arm 28 to maintain it in upright position, substantially as indicated in Figs. 1 and 2.

Extending from the upper part of the thread catcher, is a thread guide 35 which, when the lay is in its forward position, as indicated by dotted lines in Fig. 2, is closely adjacent to the surface of the chute 15 down which the discharged bobbin passes when the filling is replenished, as indicated by dotted lines in Fig. 1, the construction being such that the filling thread from the discharged bobbin or holder, as indicated by dotted lines at a, Fig. 1, will pass over the guide arm 35. With the parts in the position thus described, and indicated by Fig. 1, it is apparent that upon movement of the thread catcher clockwise, Fig. 1, about its pivotal mounting its upper portion will engage the filling thread between the shuttle box and the discharged carrier or holder, and then, by further movement, will suddenly draw or whip the filling thread a from the shuttle box and shuttle. Where the teeth 29 are employed they will positively engage the filling and more effectively insure its positive withdrawal from the shuttle and shuttle-box.

As hereinbefore pointed out, this movement of the thread catcher may be imparted from any moving part of the loom, but it is found convenient, in the present form of the invention, to give such movement to the thread catcher through the picking mechanism, and, to this end the pick or rock shaft 20 has secured thereto or projecting therefrom, a lug 36, Fig. 2, from which extends the actuating finger 37. This actuating finger may be appropriately secured to the lug 36 adjustably by the slot and bolt connection 38, as indicated in Fig. 2, or, if desired, the lug 36 might be secured to the arm 19, the purpose being to impart to the actuating finger 37, oscillatory movement of the pick or rock shaft 20.

Extending downward from the sleeve 30 which carries the thread catcher arm 28, is an arm 39, which is adapted to be actuated to turn the sleeve 30 upon the arm 26 and thereby impart to the thread catcher its described movement.

It is desirable that the thread catcher be actuated only upon call for filling replenishment, and to this end the usual slotted member 40 of the shuttle feeler and thread parter mechanism has attached thereto at 41, a connection 42 with a block 43 slidably mounted on the arm 39. This connection

42 may be of any desired character, but is conveniently formed as a flexible part, the lower end of which is secured to a pin 44 extending from the block 43. From the 5 construction described, it will be apparent that upon call for filling replenishment, the slotted member 40 connected to the shuttle feeler and thread parter, will be raised, as usual in this type of loom, thereby raising 10 the block 43 upon the arm 39 extending from the sleeve 30, and placing said block in position to be struck by the actuating finger 37 connected to the pick rock shaft 20, the construction being such that upon 15 call for filling replenishment, the parts will be operatively positioned so that on the pick following replenishment, the thread catcher will be actuated to engage and whip the thread of the discharged carrier or 20 holder from the shuttle box and shuttle; and as the pick rock shaft 20 returns to its normal position, the spring 32 will likewise return the thread catcher to its initial position.

25 Inasmuch as the block 43 is raised on the call for filling replenishment, and the latter operation takes place when the lay is in its substantially front position, as indicated in Fig. 2, it is found convenient to provide 30 means to maintain the block 43 in its raised position as the lay moves rearwardly, and until the picking mechanism has acted. As one means to this end, there is secured to the side of the loom frame by suitable means 35 45, a bracket 46 shown in detail in Fig. 3, having a bent end portion 47 through which projects a pin 48 having a supporting head 49 and normally under the influence of a spring 50 to hold the head 49 to the left, 40 Fig. 3. The spring 50 is light and of less torsional strength than the spring 32, so that when the parts are in the position as indicated in Fig. 1, the spring 50 is compressed. When, however, the block 43 is 45 raised on the call for filling replenishment, the spring 50 expands and carries the holding head 49 into position below the block 43, and thus insures a proper position of that block for contact by the actuating finger 50 37 of the picking mechanism. When the thread catcher has been actuated and turned about its pivotal support upon the arm 26, and the pick shaft 20 returns to initial position, the block 43 slides down the arm 39 55 while said arm is still inclined, and while the thread catcher is returning to initial position, with the result that the block 43 reaches its lowest position, as indicated in Figs. 1 and 2, before the thread catcher 60 comes to rest, and the parts then assume the position as indicated in Fig. 1, with the block 43 resting against the supporting head 49.

The loom frame 1 is provided with a slot 65 51 to provide for any excess movement of

the arm 39 depending from the thread catcher sleeve 30.

From the construction described, it will be noted that the thread catcher remains quiescent during the normal operation of 70 the loom and while a sufficient supply of filling is present in the shuttle; but on the call for replenishment, the thread catcher actuating means is operatively positioned to move the thread catcher and cause it to 75 engage and withdraw the old filling from the shuttle box and shuttle. It will also be noted that such withdrawal of the old filling is effected through the active movement of the thread catcher and is not dependent alone upon the backward movement of the lay. An important feature of 80 this invention is the fact that the thread catcher moves relatively to the shuttle box in withdrawing or whipping the old filling 85 end therefrom, and that this movement is in a direction away from or downward with respect to the shuttle box, thereby imparting a direct pull upon the thread. By mounting the thread catcher in the manner 90 described, and actuating the same from suitable means, such as the picking mechanism, the old filling thread is suddenly whipped from the shuttle box and shuttle at or just after the time the shuttle itself 95 is moved by the picking mechanism, and the whip-like action of the thread catcher is such that after withdrawing the old filling thread from the shuttle box and shuttle, it throws the same downward and leaves itself free 100 from engagement therewith.

What is claimed is:—

1. In a filling replenishing loom, the combination of the lay and shuttle-boxes, a thread catcher having a thread guiding portion over which the discharged carrier may pass and a toothed thread engaging portion, and means for moving the thread catcher to cause the guiding portion to deliver the thread to the toothed portion and withdraw it from the shuttle-box.

2. In a filling replenishing loom, the combination of the lay and shuttle-boxes, a thread catcher having a thread guiding portion over which the discharged carrier may pass and a toothed thread engaging portion angularly arranged with relation to the guiding portion, and means for moving the thread catcher to cause the guiding portion to deliver the thread to the toothed portion and withdraw it from the shuttle-box.

3. In a filling replenishing loom, a thread catcher to engage a thread between the discharged filling carrier and shuttle-box, and means for moving said thread catcher transversely of the loom and in a downward direction to withdraw the thread of the abandoned filling carrier from the shuttle-box.

4. In a filling replenishing loom, the combination of the lay and shuttle boxes, a thread catcher to act upon the filling between a discharged filling holder and a shuttle box, and means for imparting to the thread catcher a sudden whip-like impulse in an outward and downward direction with relation to the shuttle-box to whip the thread from the shuttle box.
5. In a filling replenishing loom, the combination of the lay and shuttle-boxes, a thread catcher comprising an arm having a portion to engage a thread extending from an abandoned filling carrier to the shuttle-box, means for supporting the arm for movement of the thread engaging portion in a downward direction in a plane transversely of the loom to withdraw the thread of the abandoned filling carrier from the shuttle-box, and means acting yieldingly to restore the arm to initial position.
6. In a filling replenishing loom, the combination of the lay and shuttle-boxes, a thread catcher comprising an arm having a portion to engage a thread extending from an abandoned filling carrier to the shuttle-box, means for moving the thread engaging portion of the arm in a downward direction in a plane extending transversely of the loom to withdraw the thread of the abandoned filling carrier from the shuttle-box after the shuttle picking movement has commenced, and means for rendering the moving means operative on call for replenishment.
7. In a loom, the combination of the lay and shuttle boxes, filling replenishing mechanism, a thread catcher below the path of movement of the shuttle boxes, means for picking the shuttle and means for moving the thread catcher in a direction opposed to the picking movement of the shuttle to withdraw or whip the thread from the shuttle box and shuttle.
8. A filling replenishing loom having a thread catcher for withdrawing the filling from the shuttle-box, comprising an arm mounted to swing in a plane transversely of the loom below the shuttle-box, and means for imparting swinging movement to said arm in the transverse plane of the loom following a call for filling replenishment to carry the thread away from the shuttle-box.
9. A loom comprising a lay and shuttle boxes, filling replenishing mechanism, a thread catcher having teeth to engage the filling positively between the shuttle box and a discharged filling holder, and means set in operative condition upon call for filling replenishment for causing the thread catcher to move downwardly and toward the adjacent end of the lay to draw the filling from the shuttle.
10. A thread catcher for filling replenishing looms, comprising an arm provided with a deflected upper portion to engage the filling below the shuttle-box and means for moving said arm outwardly away from proximity to the inner end of the shuttle-box and in a downward direction to engage the filling between the abandoned filling carrier and shuttle-box and carry the filling downwardly away from the shuttle-box.
11. In a loom, the combination of the lay and shuttle boxes, filling replenishing mechanism, picking mechanism for the shuttle, a thread catcher, and means operatively positioned with respect to the picking mechanism only upon call for filling replenishment to operate the thread catcher as the shuttle is picked.
12. In a loom, the combination of filling replenishing mechanism, a thread catcher to engage the filling between the shuttle and a discharged filling carrier, picking mechanism, means to move the thread catcher in a direction opposed to the picking movement to withdraw the filling thread from the shuttle, and mechanism for rendering said means operative to effect such movement only on call for filling replenishment.
13. In a loom, filling replenishing mechanism, a thread catcher, means operatively positioned on call for filling replenishment for imparting movement to the thread catcher transversely of the loom in a downward direction to pull the filling thread in a downward direction from the shuttle box and shuttle, and means for normally maintaining the thread catcher inoperative until the filling is to be changed.
14. In a loom, filling replenishing mechanism, a thread catcher having teeth for positively engaging and holding the filling between the shuttle box and a discharged carrier or holder, and actuating means for causing the thread catcher to move downwardly in a plane transversely of the loom to actively pull the filling from the shuttle box.
15. In a filling replenishing loom, the combination of the lay and shuttle-boxes, a thread catcher comprising an arm pivotally mounted below the shuttle-box at the replenishing side of the loom, a spring normally acting to maintain the thread catcher in initial position, and means for imparting to the thread catcher a swinging movement in a plane transversely of the loom to engage the filling between the shuttle-box and discharged filling carrier and withdraw the filling from the shuttle-box.
16. In a filling replenishing loom, the combination of the lay and shuttle-boxes, a thread catcher pivotally mounted below the path of movement of the lay at the replenishing side of the loom to swing in a plane transversely of the loom and in a direction toward the outer end of the shuttle-

box and having a deflected or bent upper portion to engage the filling between the shuttle-box and discharged filling carrier, and means to actuate the thread catcher 5 after a replenishing operation to withdraw the old filling from the shuttle-box.

17. In a filling replenishing loom, the combination of the lay and shuttle-boxes, a thread catcher comprising an arm pivotally 10 mounted at the replenishing side of the loom to swing in a plane transversely of the loom in a downward and outward direction relative to the inner end of the shuttle-box, a spring normally acting to maintain the 15 thread catcher in a position of rest, and means rendered operative upon call for filling replenishment for actuating the thread catcher to withdraw the old filling from the shuttle-box after the filling has been 20 changed.

18. In a filling replenishing loom, the combination of the lay and shuttle-boxes, a thread catcher to engage the filling between the shuttle-box and discharged filling carrier or bobbin, a transverse or change shaft 25 and means rendered operative by movement

of said shaft for moving the thread catcher in a plane transversely of the loom in a direction opposite the picking movement of the shuttle to withdraw the old filling. 30

19. In a filling replenishing loom, the combination of an arm having a part to engage the thread of the discharged filling carrier below the shuttle-box, means for moving the arm in a direction transversely of the loom toward the outer end of the shuttle-box and downwardly to withdraw the thread from the shuttle-box, means for normally holding said arm in inoperative position, means rendered effective upon call for filling 35 replenishment for operating said arm to withdraw the old filling from the shuttle and shuttle-box as the shuttle moves toward the opposite shuttle-box.

In testimony whereof, I have signed my 45 name to this specification, in the presence of two subscribing witnesses.

HENRY J. HEDLER.
